ABSTRACT: A tool for extracting a light bulb base from a socket comprises an extractor member which is partially insertable into the bulb base to frictionally engage the sidewall thereof upon the tapered outside surface of the extractor member. An aperture is defined in one end of the extractor member into which the filament support stem of the light bulb may be inserted and engaged against relative rotation. Engagement of the sidewall and stem cooperate to provide a dual effect for removing the remains of the light bulb from the socket.

ATTORNEY

LIGHT BULB BASE EXTRACTOR

BACKGROUND OF THE INVENTION

Frequently, the glass bulb portion of a conventional light bulb becomes broken while the bulb is securely mounted in an electrical socket, and when this occurs, the portions which remain are generally inadequate to provide the necessary gripping surface to unscrew or otherwise effect removal thereof. Moreover, in many instances the fragments of glass which do remain on the base make the safe handling thereof impossible without protection of some sort.

Prior art devices have been furnished which are designed to ream the glass out of the bulb base so as to make handling less dangerous, but the problem still remains, with such devices, that the gripping surfaces are insufficient if the bulb is securely mounted in the socket. Other prior art devices rely solely upon a frictional engagement with the sidewall of the base, and whereas certain of these devices are relatively simple the security with which they engage the base is often not adequate to effect the removal thereof. More complex devices which are available may provide more secure engagement with the base, but they tend to be relatively expensive and are often inconvenient to employ, particularly when space for manipulation is limited or when used from a distance, e.g., when a ceiling fixture is involved.

Accordingly, it is an object of the present invention to provide a novel tool for safely removing broken light bulb bases from their sockets and which is relatively simple and economical to manufacture.

Another object is to provide such a tool in which a dual effect may be relied upon to effect the removal of the bulb base.

Still another object is to provide such a tool which may effectively be utilized at a distance considerably removed from the broken light bulb, or where space for manipulation is limited.

BRIEF DESCRIPTION OF THE DRAWING

FIG. 1 is a fragmentary longitudinal view of a tool embodying the present invention aligned beneath the remains of a broken light bulb mounted in an overhead fixture;

FIG. 2 is a fragmentary longitudinal view of the tool of FIG. 1 with the extractor member thereof engaged with the base of the broken bulb;

FIG. 3 is a fragmentary perspective view to an enlarged scale of the tool of FIGS. 1 and 2;

FIG. 4 is a sectional view along the line 4-4 of FIG. 2 drawn to an enlarged scale wherein there is shown the extractor member partially inserted into the bulb base and engaged with the base and filament support stem thereof;

FIG. 5 is a sectional view along the line 5-5 of FIG. 2 and drawn to an enlarged scale; and

FIG. 6 is a fragmentary perspective view of another embodiment of the tool of the present invention.

SUMMARY OF THE INVENTION

It has now been found that the foregoing and related objects can be readily attained in a tool which comprises an extractor member having an external cross section of maximum dimension at a point spaced from one end thereof. The extractor member tapers from that point to the end from which it is spaced, and the maximum external dimension and the external dimension at the end are, respectively, greater and lesser than the diameter at the entrance of the bulb base with which the tool is to be used.

Axially extending, spaced apart portions of the extractor member define an aperture therebetween which opens at the tapered end, and the aperture is dimensioned to receive a filament support stem of the type which has a major cross-sectional dimension and a smaller minor cross-sectional dimension projecting axially from the base. The aperture is wider than the minor dimension and narrower than the major dimension of the stem so that the stem may be axially seated in the aperture and engaged therein against relative rotation. Thus,

the extractor member may be partially inserted into the base with the stem thereof engaged against relative rotation, and with the sidewall of the base frictionally engaged on the tapered outside surface of the extractor member between the end and the spaced point of maximum dimension.

The extractor member may comprise a plurality of axially extending elongated fingers extending from a common base located at the end of the extractor member opposite from the tapered end. The fingers are preferably circumferentially equidistantly spaced on the base and each one has an axially outwardly extending knuckle spaced from the tapered end to provide the necessary maximum dimension external cross section. The fingers may be relatively rigid or radially resiliently deflectable and most desirably four fingers will be provided by the extractor member.

Alternatively, the extractor member may comprise a generally solid element having an axially extending, elongated recess opening at the tapered end with a noncircular transverse cross section, preferably oval. In such an embodiment, the spaced apart portions are provided by opposite sidewalls defining the recess at a relatively small dimension of the transverse cross section. Most desirably, the tool will include a handle joined to the extractor member at the end thereof opposite the tapered end, and the handle and extractor member may be integrally formed as a single piece, such as by molding a synthetic resin.

DETAILED DESCRIPTION OF THE ILLUSTRATED EMBODIMENT

30

Turning now in detail to FIGS. 1-5 of the drawing, a tool embodying the present invention has an elongated handle 10 with a grip element 12 at one end and an extractor member, generally designated by the numeral 14, secured to the other end thereof. The extractor member 14 is integrally formed with four axially extending elongated fingers 16 spaced equidistantly about the common base element 17. The fingers 16 each have an axially extending knuckle 19 spaced from the free ends thereof providing a maximum external cross-sectional dimension which is larger than the diameter at the entrance 30 of the base 22 of the broken light bulb, generally designated by the numeral 18, with which the tool is to be employed. The dimension *b* at the free ends of finger 16 is smaller than that diameter so that, as is best seen in FIGS. 2 and 4, the extractor member 14 may be inserted into the bulb base 22 so that the tapering outside surfaces 28 frictionally engage the sidewall of the base 22 at the entrance 30 thereof.

The radial and circumferential spacing between the fingers 16 is sufficient to permit the relatively wide filament stem 24, projecting axially from the base 22, to be seated in the aperture 34 defined by the inside edges 32 of diametrically opposed fingers 16' (so designated in FIGS. 4 and 5 only for the purpose of illustration). Since the spacing *c* of the aperture 34 is greater than the thickness *t* and lesser than the width *w* of the stem 24, the stem 24 can be seated in the aperture 34 so that rotation of the tool causes the inside edges 32 of the fingers 16' to bear upon and exert a twisting moment to the stem 24.

60 Operation of the tool illustrated in FIGS. 1-5 will be readily apparent. As is shown in FIGS. 1 and 2, the extractor member 14 is partially inserted into the base 22 of a broken light bulb mounted in an overhead fixture 20. The light bulb has a conventional right-hand threaded base 22 from which projects the relatively wide, elongated filament support stem 24; glass fragments 26 remain attached to the base 22 after the main portion of the glass bulb is broken away. In the manner described, the extractor member 14 frictionally engages the entrance 30 of the base 22 on the outside tapered surfaces 28 of the fingers 16, and seats the stem 24 in the aperture 34. Upon rotation of the tool in the counterclockwise direction the inside edges 32 of the fingers 16' bear upon opposite sides of the stem 24 to engage it against relative rotational movement, whereby the engagement between the base 22 and fila-

75

ment stem 24 and the extractor member 14 provides a dual engagement by which the base 22 may readily be unscrewed from the socket and extracted therefrom.

FIG. 6 illustrates an alternate embodiment of the invention in which a generally solid extractor member, generally designated by the numeral 40, has an octagonal exterior configuration providing eight edges 42, and an elongated axially extending recess 44, which is oval in transverse cross section. The opposite sidewalls 46 of the recess 44, at a relatively small transverse cross section thereof, define, in longitudinal cross section, an aperture having a dimension indicated by x .

As in the previous figures, the extractor member 40 is employed with a light bulb base having a filament support stem with a major dimension and a smaller minor dimension projecting therefrom. The recess 44 is dimensioned to axially receive the stem of the light bulb, but the small dimension x of the recess 44 is larger than the minor dimension of the stem and smaller than the major dimension thereof. Thus, the stem may be seated in the aperture provided by the recess and engaged against relative rotation. The large transverse cross section of the member 40 at 48 is larger than the diameter of the entrance of the bulb base with which it is to be used, and the small cross section thereof at 50 is smaller than that diameter, so that upon insertion of the small end the edges 42 frictionally engage the sidewall of the base and cooperate to effect the removal thereof.

The configuration of the extractor member may vary considerably and is not restricted to those of the illustrated embodiments. Any structure which will provide both the outside surface for frictional engagement and the axial aperture for seating the filament support stem may be employed. However, the embodiment of the invention which is preferred is that which utilizes a plurality of fingers. Most desirably, the tool is designed so that fingers of the extractor member can exert force simultaneously on the opposite sides of the stem, and this may be accomplished most readily by two diametrically opposed fingers between which the stem may be diagonally seated. Since a multiplicity of fingers providing spacing therebetween to receive the filament support stem may facilitate operation, such an arrangement is generally preferable. However, the spacing of the fingers should be adequate to allow the support stem of the bulb to be inserted therebetween, and thus a practical limit upon the maximum number of fingers which may be present exists, if the stem is to be accommodated therebetween. Furthermore, since the extractor member most effectively has fingers in diametrically opposite positions, an even number of fingers is usually found to be best. In view of all of these considerations, 2 or 4 fingers will usually be employed although it is to be understood that the invention is not so limited.

The fingers must be spaced apart a sufficient distance to allow the filament support stem of the bulb base to fit therebetween, and this is true both as regards the minimum circumferential spacing of adjacent fingers and the radial spacing of diametrically opposed fingers. If the stem is considered to have a major dimension and a minor dimension relative thereto, the spaces must be great enough to accommodate the minor dimension. However, the space between the inner edges of at least 2 fingers must be less than the major dimension of the stem so that the fingers can engage it against relative rotation. Accordingly, the inner edges of the fingers define, in longitudinal cross section of the extractor member, at least one aperture opening towards the tapered end of the member which is wider than the minor dimension and narrower than the major dimension of the stem, and which is normally generally U-shaped. It will be appreciated that the sides of adjacent fingers define voids therebetween into which the stem may extend radially, thus accommodating the major dimension of the stem while it is seated against relative rotational movement in the aperture; it will be clear that the radial depth of these voids is not what is referred to herein as the "spaces."

The extractor member may also be a relatively solid element having an axially extending recess therein, dimensioned and configured to accommodate the stem projecting from the light bulb base. In such an embodiment, the transverse cross-sectional dimensions of the recess will correspond roughly to those of the stem of the bulb base for which the tool is designed to be used. That is, the recess will have a major and minor dimension sufficiently large to allow insertion of the stem, but the minor dimension of the recess must be smaller than the major dimension of the stem so that the stem and tool may not be rotated relative to one another beyond a given point. Ordinarily a recess which is generally oval in transverse cross section will conveniently furnish the aperture for seating the bulb stem, but a polygonal recess capable of receiving the stem axially and engaging it against relative rotation may be utilized. It should be understood that when the aperture is provided by a recess, any two points on opposite sides of the walls defining the recess may be considered to define the aperture as long as they are separated by a distance lesser than the major cross-sectional dimension of the light bulb stem.

The outer cross section of the extractor member should be tapered so that it may be partially inserted into the bulb base, and provide an outside surface for frictional engagement with the base sidewall. Therefore, the extractor member will have its maximum transverse cross section at a point spaced from the insertable end, and this point may be intermediate the ends or at the opposite end thereof. It should be understood that the surface extending between the wide and narrow points need not be rectilinear, and that the term "tapered" includes curved surfaces as well.

The dimensions of the spaces providing the apertures in the extractor members and the cross-sectional dimensions determining the configuration of the tapered outside surface cannot be defined specifically since they depend upon the size and configuration of the bulbs for which the tool is designed to be used. However, to make the tool useful for as wide a variety of light bulbs as possible, the largest dimensions of the outside of the extractor member may be considerably larger than the smallest dimensions thereof, and the internal spaces may be optimized to engageably receive as wide a range of stem sizes as possible. Although the tools of the present invention may advantageously be furnished in a number of different sizes since the size of light bulbs varies considerably, it is possible to adapt a single tool to a broad range of bulb sizes. For example, temporary inserts may be provided to decrease the size of the recess in a generally solid element in order to adapt it for use with smaller light bulbs or, when the extractor member has a plurality of fingers, means may be provided for adjusting the span thereof and/or the spacing therebetween. Other possibilities that will occur to those skilled in the art are also considered to be within the scope of the present invention.

If the extractor member is comprised of a plurality of fingers, they may either be relatively rigid or radially resiliently deflectable. The rigid fingers may be inserted into the bulb base with sufficient force to deform the sidewall thereof to create a slight but effective mechanical interlock therebetween, and this effect may be enhanced by providing the outside edges of the fingers with sharpened surfaces. If the fingers are resiliently deflectable, the extractor member may be inserted well into the base so that contact with the sidewall is established over a considerable length of the outside surface, rather than at a single point thereon. Such resiliency may also be advantageous from the standpoint of adapting one tool to a fairly broad range of light bulb sizes.

The generally solid type of extractor members can be rigid or deformable or deflectable, but the latter type may be preferred. Since the solid member will generally provide a continuous circumferential surface for engagement, the applied force will generally not be sufficient to cause deformation of the sidewall, as can be done with narrow or sharpened fingers, i.e., the force is distributed over a much greater surface area. However, the rigid member need not have a circular exterior configuration (e.g., it may be polygonal), or it may be

fluted, serrated or otherwise modified to provide narrow or even sharp edges; frictional engagement may be greatly enhanced by such modifications.

The extractor member should have a handle secured to one end, and most desirably the handle is elongated for use with ceiling or other difficult to reach fixtures. The handle may be a very simple pole member or it may be quite complex, such as by including means by which it may be disengaged from the extractor member or by making it adjustable in length; a gripping element may also be furnished at the opposite end of the handle.

The tool and its component parts may be made of a wide variety of material, such as wood, metal, synthetic resin, rubber, etc., and combinations of such materials may be utilized. The handle may be made of wood or metal and joined to an extractor member or rubber or resin, the extractor member may itself have a body of one material with a second material providing the engagement surfaces thereof, or the entire device may be fabricated of a single material, such as a resin, rubber or metal. Use of a single material for the extractor member generally offers significant advantages in terms of economy and facility of manufacture since the number of operations involved can thereby be minimized. If, for example, a synthetic thermoplastic material is utilized, a commercially acceptable finished tool can be produced in a single operation, such as by injection or compression molding techniques. On the other hand, certain material (e.g., wood) may be inherently less expensive, or may operate more effectively, and these factors should also be considered in determining the particular material or combination thereof to be employed. It should also be borne in mind that it may be necessary to use the tool with a bulb base in a current-carrying circuit so that the material thereof should be capable of protecting the user against possible shock and of preventing short circuits. Accordingly, at least the contact surfaces of the extractor member should be of an insulating material or should be insulated from one another, and some insulation should be present to protect the user, e.g., in the handle or gripping element. Such problems are readily avoided by fabricating the entire tool of a convention synthetic resin or the extractor member of synthetic resin and the handle of wood.

Although use of the present tools for the removal of broken light bulbs having threaded bases has been stressed in the foregoing description, it should be appreciated that these devices may also be employed with the so-called "bayonet-type" of bases or any other type of base which is turned to remove it from its socket. It should also be understood that, although the tool is designed to take advantage of the dual effect of engagement with both the sidewall and the filament support stem of the light bulb, either of these effects may be relied upon independently in a given instance, albeit with reduced effectiveness.

Accordingly, it can be seen that the present invention provides a novel tool for safely extracting broken light bulb bases from their sockets. The tool is relatively simple and economical to manufacture, and it provides a dual effect by which the bases may be readily removed. It may be effectively employed at a distance from the broken light bulb or where space for manipulation is limited.

I claim:

1. A tool for extracting a light bulb base from a socket comprising an extractor member having one end insertable into a light bulb base, said extractor member having an external cross section of maximum dimension at a point spaced from said one end, said maximum dimension being greater than the

internal diameter at the entrance of the light bulb base with which said tool is to be employed, the external cross section of said member tapering toward said one end to a dimension less than the entrance diameter of the light bulb base to provide a

5 tapering outside surface, said member comprising a common base at the other end thereof with a plurality of radially spaced, elongated fingers extending axially therefrom, said fingers being equidistantly spaced about said base with a void defined between the sides of each adjacent pair thereof, said 10 fingers thereby defining an axially extending, substantially obstruction free aperture therewithin opening at said one end and dimensioned to permit insertion therewith of a filament support stem which projects outwardly from the base and which has a major cross-sectional dimension and a minor cross-sectional dimension less than the major dimension, said aperture being wider than the minor dimension and narrower than the major dimension so that the stem of the base may be 15 axially seated in said aperture with the major dimension thereof extending into voids on opposite sides of said common base and engaged therein against relative rotation, said one 20 end being partially insertable into the base so that it frictionally engages the base at the entrance thereof on said tapering outside surface.

2. The tool of claim 1 wherein each of said fingers has an axially outwardly extending knuckle spaced from said one end providing said maximum dimension external cross section.

3. The tool of claim 2 wherein said fingers are relatively rigid.

4. The tool of claim 2 wherein said fingers are radially resiliently deflectable.

5. The tool of claim 2 wherein said plurality of fingers comprises four fingers.

6. A tool for extracting a light bulb base from a socket comprising an extractor member having one end insertable into a 35 light bulb base, said extractor member having an external cross section of maximum dimension at a point spaced from said one end, said maximum dimension being greater than the internal diameter at the entrance of the light bulb base with which said tool is to be employed, the external cross section of said member tapering toward said one end to a dimension less than the entrance diameter of the base to provide a tapering outside surface, said member comprising a generally solid element having an axially extending, elongated recess in said one end with a noncircular transverse cross section, said recess 40 opening at said one end being dimensioned to permit insertion therewith of a filament support stem which projects outwardly from the base and which has a major cross-sectional dimension and a minor cross-sectional dimension less than the major dimension, said recess being wider than the minor dimension and narrower than the major dimension so that the stem of the 45 base may be axially seated in said recess and engaged therein against relative rotation, said one end being partially insertable into the base so that it frictionally engages the base at the entrance thereof on said tapering outside surface.

7. The tool of claim 6 wherein said extractor member has a polygonal external configuration providing edges for enhanced frictional engagement.

8. The tool of claim 6 wherein said transverse cross section is generally oval.

9. The tool of claim 1 wherein an elongated handle is secured to the other end of said extractor member.

10. The tool of claim 9 wherein said extractor member is integrally formed of a synthetic resin having good electrical insulating properties.
